RACING CAR

Anthony Cyril Rudd, Darlaston, England, assignor to Rubery, Owen & Company Limited, Darlaston,
England, a British company

Filed Sept. 30, 1966, Ser. No. 4,109

Claims priority, application Great Britain Apr. 2, 1966

Term of patent 3½ years

(Cl. D14—3)

The dominant features of my design reside in the portions shown in full lines.

I claim:

The ornamental design for a racing car, as shown and described.
